UNITED STATES PATENT OFFICE.

FRANK D. WARREN, OF COLORADO SPRINGS, COLORADO.

ELECTRICAL FLY-KILLER.

1,058,680.

Specification of Letters Patent.

Patented Apr. 8, 1913.

Application filed September 20, 1912. Serial No. 721,366.

To all whom it may concern:

Be it known that I, FRANK D. WARREN, a citizen of the United States, residing at Colorado Springs, in the county of El Paso 5 and State of Colorado, have invented certain new and useful Improvements in Electrical Fly-Killers, of which the following is a full, clear, and exact description, reference being had to the accompanying drawing.

Since it is the nature of flies to seek the light and in so doing to swarm and crawl upon the inner surface of the window glass, the object of this invention is to provide 15 a cheap, simple and effective device for terminating the flies as they crawl upon the window.

Other objects and advantages of the invention will be set forth in the ensuing description.

Referring to the drawing, Figure 1 shows a fragmental, elevation view of an ordinary window with the electrical fly killer attached to the sash. Fig. 2 is an enlarged, 25 perspective illustration of brackets F and K.

The electric fly killer consists of two wires or bars, C and D respectively, charged with electricity of sufficient intensity to electrocute a fly crawling across the said bars and 30 thereby closing the circuit. The bars C and D are strung across the inner surface of the window glass B in such a manner as to intercept the passage of the flies, and close enough to the window glass to allow the 35 flies to crawl over the said bars. The end E of bar D is secured to the bracket F by being laced through holes R and S in said bracket and then clenched. The end G of bar C, being insulated, passes through a 40 hole V in bracket F and is gripped by downwardly extending flanges H integral with bracket F, said flanges being adapted to clamp the insulation of the said bar C by being bent over upon it. Bracket F is 45 placed in contact with the window glass B

and secured to the window sash A by means of a screw I, passing through the hole T in the base W of the said bracket F. Bars C and D are secured at the opposite side of the window sash A by means of a bracket 50 K similar to bracket F. The free end M of bar D is to be connected to the negative pole, and the free end N of bar C to the positive pole of a battery or induction coil adapted to give a current of the 55 required intensity.

The foregoing being a full, clear and exact description of the invention, what I claim and desire to secure by Letters Patent is:—

In combination with two or more parallel bars stretched across the surface of a window pane and electrically energized and adapted to electrocute flies, said bars being supported by brackets adapted to hold them 60 in position, an upper arm of said bracket adapted to afford gripping means for holding the end of the upper bar, a plurality of holes in the said upper arm adapted to receive the end of the upper bar, the end of 65 the upper bar adapted to be clenched, a lower arm of said bracket adapted to afford gripping means for holding the end of the lower bar, a hole in the outer end of the said lower arm adapted to receive the insulated end of the said lower bar, depending 70 clamps integral with the said lower arm adapted to afford suitable gripping means for holding the end of said lower bar, a base integral with the said upper and lower 75 arms and forming a part of the said bracket, a hole in the said base adapted to receive a screw to secure the said bracket to the window sash.

Witness my hand this 17th day of Sept., 85 1912.

FRANK D. WARREN.
